LAMP SHADE

Elizabeth Brown, Plainfield, N. J.

Application March 2, 1940, Serial No. 321,857

1 Claim. (Cl. 246—108)

This invention relates to lamp shades, and particularly to lamp shades having a fabric lamp shade body.

One feature of the invention is the provision of a lamp shade having a lamp shade body which is readily removable to enable it to be cleansed in a simple and safe fashion and then replaced upon the lamp shade, or to be replaced by a lamp shade body of a different design or texture.

Other features of the invention and its advantages will become apparent from the following description taken in connection with the accompanying drawing in which:

Fig. 1 is a vertical elevation, partly in section, of a lamp shade according to the invention;

Figs. 2 and 3 are enlarged details of portions of the lamp shade shown in Fig. 1; and

Fig. 4 is a perspective view of the upper portion of the lamp shade with the trimming turned down to expose the slide fastener.

Referring to the drawing the lamp shade generally designated 10 comprises a frame 11, a lamp shade body 12 and a separable fastening means 13 and 14 around the top and bottom of the shade, respectively, fastening the lamp shade body 12 to the frame 11.

The frame 11 includes an upper metallic ring 15 and a lower metallic ring 16 connected by a plurality of metallic rods 17 spaced around the periphery of the rings. In the shade illustrated the rings 15 and 16 and rods 17 are enclosed by a cloth covering 18, conveniently applied by wrapping the same with fabric strips, and the upper ring 15 is smaller in diameter than the lower ring 16.

The frame illustrated also includes a shade lining 19 secured thereto between the rings 15 and 16, and shade supporting rods 20 secured to the upper ring 15.

The frame 11 has secured around its upper edge one tooth-strip member, 21a, of the upper, interlocking separable slide fastener 13, the member shown having its teeth secured to a flexible fabric strip which in turn is sewn to the cloth covering 18 enclosing the upper ring 15. Similarly, the frame 11 has secured around its lower edge one tooth-strip member, 22a, of the lower interlocking slide fastener 14, the member shown having its teeth secured to a flexible fabric strip which in turn is sewn to the cloth covering 18 enclosing the lower ring 16.

The lamp shade body 12 is cut and seamed together so as to give it a skirt or tubular shape of suitable shape and proportions to fit relatively snugly upon the frame 11. The lamp

shade body 12 has the other tooth-strip member, 21b, of the upper fastener 13 secured along the top edge of the body 12 and has the other tooth-strip member, 22b, of the lower fastener 14 secured along the bottom edge of the body 12. The members 21b and 22b shown have their teeth formed on flexible fabric strips which are sewn to the lamp shade body 12.

Each of the fasteners 13 and 14 includes a slider 23 which causes the teeth of the abutting tooth-strip members of the corresponding fastener to interlock or mesh together as the slider is moved over them in one direction, and which causes the teeth to separate as the slider is moved over them in the opposite direction, thereby releasably securing the top and bottom edges of the lamp body to the frame 11 all around the periphery of the shade.

Further description of the slide fasteners 13 and 14 and of the details of their construction which enable complete separation of the lamp body 12 from the frame 11, and the reassembly of the same, is believed unnecessary.

If desired, the fasteners 13 and 14 may be rendered invisible by a trimming 24 secured around the top and bottom of the lamp body 12, as shown in the drawing.

The lamp body 12 is removed from the lamp shade by moving the sliders 23 at the top and bottom of the shade in the direction to separate the body from the frame. The body may then be cleaned as readily as any fabric article, in any desired liquid and manner depending upon the fabric of which it is made. Thus, if the body is made of washable fabric such as is the body shown, it may be submerged in and washed with soap and water and dried while detached and without the use of a shaping frame, and then resecured to the lamp frame by placing it in position and moving the sliders in the engaging direction. With a lamp shade of frustoconical shape as shown, this is conveniently done by first fastening the upper or small-diameter edge of the lamp shade body to the frame, and then fastening the lower or large-diameter edge.

As a result of the foregoing construction, the lamp shade may, with a minimum of difficulty and expense, be kept fresh and clean, and also have its appearance altered according to the tastes of the user. In addition, the foregoing construction enables a close fitting lamp shade body to be placed readily upon a lamp frame and maintained in place, thereby obtaining a fabric cover lamp shade having a trim, taut ap-

pearance and maintaining the lamp shade in such condition.

I claim:

In a lamp shade having a relatively stiff frame with an upper ring, a lower ring and a plurality of circumferentially spaced tie rods connecting said rings, the combination with a lamp shade body of generally tubular shape and limp material, of means for securing the lamp shade body to the frame and adapted to permit ready removal therefrom and re-attachment thereto, said means automatically aligning the upper and lower peripheries of the body with each other as the

body is fastened to the frame and also causing the frame, when the body is secured thereto, to put the body under generally axial tension all around its periphery, whereby the limp lamp shade body automatically is caused to assume its normal intended appearance each time it is fastened to the frame and caused to maintain that appearance while fastened to the frame, said means consisting of separable slide fastening means securing the top edge of the body to the upper ring and securing the bottom edge of the body to the lower ring.

ELISABETH BROWN.
